United States Patent

Des. 241,774
Patented Oct. 5, 1976

241,774

PRINTER/KEYBOARD APPARATUS FOR AN ELECTRONIC TYPING SYSTEM OR SIMILAR ARTICLE

Robert A. Clowe, Penfield, N.Y., assignor to
Xerox Corporation, Stamford, Conn.

Filed Dec. 20, 1974, Ser. No. 535,002

Term of patent 14 years

Int. Cl. D18—01

U.S. Cl. D64—11 A

FIG. 2

FIG. 3

FIG. 4

FIG. 1 is a left-hand front perspective view of a printer/keyboard apparatus for an electronic typing system or similar article showing my new design;

FIG. 2 is a front elevational view thereof;

FIG. 3 is a rear elevational view thereof;

FIG. 4 is a top plan view thereof;

FIG. 5 is a left side elevational view thereof; and

FIG. 6 is a right side elevational view thereof.

I claim:

The ornamental design for a printer/keyboard apparatus for an electronic typing system or similar article, as shown and described.
